UNITED STATES PATENT OFFICE.

CARL VALL, OF ROCHESTER, NEW YORK.

CAN-SERVER.

1,311,669.

Specification of Letters Patent. Patented July 29, 1919.

Application filed April 7, 1919. Serial No. 288,073.

To all whom it may concern:

Be it known that I, CARL VALL, a subject of the King of Italy, residing at Rochester, in the county of Monroe and State of New York, have invented certain new and useful Improvements in Can-Servers; and I do hereby declare the following to be a full, clear, and exact description of the same, reference being had to the accompanying drawings, forming a part of this specification, and to the reference-numerals marked thereon.

My present invention relates to receptacles and more particularly to holders for use in serving canned liquids such as evaporated milk, syrup, etc. and it has for its object to provide a simple, efficient and convenient serving device of this nature which may be cheaply manufactured and sold at a moderate price and which will be neat and attractive in appearance and easy to clean. To these and other ends the invention resides in certain improvements and combinations of parts all as will be hereinafter more fully described, the novel features being pointed out in the claims at the end of the specification.

In the drawings:

Figure 1 is a side view of a can server 30 constructed in accordance with and illustrating one embodiment of my invention;

Fig. 2 is a rear view thereof;

Fig. 3 is a top view with the cover raised and showing the manner in which the can 35 is inserted;

Fig. 4 is a view similar to Fig. 3 showing the relationship with the can after the latter has been punctured, and

Fig. 5 is a fragmentary horizontal section on the line 5—5 of Fig. 1.

Similar reference numerals throughout the several views indicate the same parts.

The device comprises generally a container conforming to the shape of the can 45 and adapted, in the present instance, to tightly inclose and conceal it and provided on the container wall is a spout having a knife at the base thereof which punctures the can and opens the passage into the spout 50 through which the contents may be poured, as needed in ordinary table use. This arrangement provides a more sightly, clean and convenient mode of use than is otherwise possible in serving from the original 55 package.

Referring to the drawings, 1 indicates the

container and 2 a spout having a fixed relation thereto and attached near the bottom thereof as by solder or usual ways. The container is resilient and expansible and in 60 the present instance, comprises a wide band of sheet metal adapted to embrace and encircle the can and to extend from the top to the bottom thereof. One end of the band is indicated at 3 and has attached thereto a 65 suitable handle 4. The other end abutting end is indicated at 5 and the spout 2 is preferably attached nearer this end so that as the ends are spread apart, the puncturing knife 6 on the inside of the band at the 70 base of the spout will have considerable movement. The knife itself is shown to be of a known form comprising two angularly arranged inclined blades so that the knife is angular in cross section and tapered to a 75 point. It is part of the perforated plate (not shown) spanning the base of the spout and is rigidly connected thereto and to the container or band.

In use, the can is inserted through the top 80 of the band or container, as shown in Fig. 3, being arrested in position and thereafter supported by a flange 7 at the bottom. The can, indicated at A fits into and reacts 85 against the end portion 3 while the end portion 5 is flexed outwardly so that the band is expanded and the container, as such, distended, this action being assisted by the cam action of the inclined knife 6 as the bottom edge of the can is forced past it. After 90 this position of Fig. 3 has been reached, the end 5 of the band is pressed into abutment with the end 3. In other words, the container is restored by external squeezing pressure to its normal condition which causes the 95 knife 6 to puncture the can near the bottom and permit its contents to flow into the spout 2. The ends 3 and 5 are then secured at the bottom by a catch 8 on the latter co-operating with the keeper projection 9 on the former. At the top, they are secured and the can closely confined by the flange 10 of a suitable cover 11 hinged to the band and, in the present instance, to the end 3 thereof at a point 12 just above the handle 4. When 105 this cover is in closed position, it imparts firmness and rigidity to the whole structure.

If necessary, a gasket (not shown) or other form of packing may surround the knife 6 at the base of the spout to press 110 against the exterior of the can and the interior of the container to prevent possible

leakage at this point. A knife 13 may also be provided on the cover 11, preferably near its hinge as indicated in dotted lines in Fig. 1, to puncture the top of the can A and allow 5 air to enter so that the contents will flow freely.

A device constructed in accordance with my invention is of neat and attractive appearance and easily cleaned while its manufacture does not require any fine adjustments of parts or expensive joints and fittings.

I claim as my invention:

1. In a can server, the combination with a band of resilient material adapted to embrace a can and having separable end portions, of a relatively rigid pouring spout fixed to the outside of the band and having a knife at its base on the inside of the band adapted to puncture the can when the band 20 is compressed against the latter.
2. In a can server, the combination with a band of resilient material adapted to encircle a can and having separable end portions, of a relatively rigid pouring spout 25 fixed to the outside of the band and having a knife at its base on the inside of the band adapted to puncture the can when the band is compressed about the latter, and a catch for holding the two ends of the band together.
3. In a can server, the combination with

a band of resilient material adapted to encircle and inclose a can and having separable end portions, of a relatively rigid pouring spout fixed to the outside of the band 35 and having a knife at its base on the inside of the band adapted to puncture the can when the band is compressed about the latter, and a flanged cover hinged to the band and adapted to hold it compressed about the 40 top thereof.

4. In a can server, the combination with a band of resilient material adapted to encircle and inclose a can and having separable end portions, of a relatively rigid pouring 45 spout fixed to the outside of the band and having a knife at its base on the inside of the band adapted to puncture the can when the band is compressed about the latter, a catch for holding the two ends of the band 50 together at the bottom, and a flanged cover hinged to the band and adapted to hold it compressed about the top thereof.

5. In a can server, the combination with a band of resilient material having separable end portions movable toward and from each other and adapted to embrace a can, of a relatively rigid pouring spout fixed to the outside of the band on one of such movable portions and means for puncturing the 60 can at the base of the spout.

CARL VALL
